UNITED STATES PATENT OFFICE.

ASHLEY J. GULICH, OF CLEARFIELD, PENNSYLVANIA.

CIRCULAR-KNITTING MACHINE.

SPECIFICATION forming part of Letters Patent No. 623,539, dated April 25, 1899.

Application filed July 9, 1898. Serial No. 685,500. (No model.)

To all whom it may concern:

Be it known that I, ASHLEY J. GULICH, a citizen of the United States, residing at Clearfield, in the county of Clearfield and State of Pennsylvania, have invented a new and useful Circular-Knitting Machine, of which the following is a specification.

This invention relates to circular-knitting machines; and it has for its object to effect certain improvements in machines of this character to provide for simplifying the construction thereof while at the same time insuring a uniform and positive operation.

To this end the invention primarily contemplates improved means for rotating the revolute cam ring or head in either direction without the use of the cog-gearing or other devices usually resorted to for imparting motion to this part of the knitting-machine, thereby greatly simplifying the machine and also permitting the same to be manipulated with much greater facility.

While one of the essential features of the present invention is the provision of a handle or crank-arm attachment for the cam ring or head to provide for the rotation of the latter in either direction without the use of cog-gearing or similar mechanism, the invention also has for its object to provide a new and useful form of yarn-carrier rotating with the revolute cam ring or head and having an improved yarn take-up and lock; and as a general object the invention has in view an improvement in the mounting of the various parts, especially of the needle - actuating cams, whereby all parts of the machine are readily accessible for the purposes of adjustment or repair.

With these and other objects in view, which will readily appear as the nature of the invention is better understood, the same consists in the novel construction, combination, and arrangement of parts, hereinafter more fully described, illustrated, and claimed.

In the drawings, Figure 1 is a perspective view of a circular-knitting machine embodying the improvements contemplated by the present invention. Fig. 2 is a vertical sectional view at one side of the plane of the yarn-carrier. Fig. 3 is a detail in perspective of the revolute cam ring or head with the yarn-carrier and crank-supporting bracket

attached and shown removed from the base-ring and needle-cylinder. Fig. 4 is a fragmentary sectional view of the cam ring or head, showing the arrangement and relative position of the needle-controlling cams. Fig. 5 is a detail sectional view showing the adjustable connection of the pendent yarn-guide arm with the crank-arm or handle-lever. 60

Referring to the accompanying drawings, the numeral 1 designates the horizontal base-ring of the machine, provided at one side with a clamp 2, by means of which the machine can be readily secured to a table, shelf, or similar support. The separate upper and lower members of the clamp 2 are preferably formed integral with the base-ring casting, and one of said clamp members has mounted therein the clamping-screw 3, which forms 70 the working member of the clamp and provides for the ready attachment of the machine to its support.

The horizontal base-ring 1 of the machine is formed in its upper side with an annular 75 guide rabbet or groove 4 and has fastened to its upper side and at the inner peripheral edge thereof, by means of the screws or similar fastenings 5, the lower end of the upright needle-cylinder 6. The said needle-cylinder 80 6 is thus rigidly connected with the base-ring, so as to form a stationary part of the machine, and said needle-cylinder is of the ordinary construction, being provided in its exterior face with a circumferential series of 85 vertically-disposed needle channels or grooves 7, in which reciprocate the vertically-movable knitting-needles 8. The said knitting-needles are retained within their guide channels or grooves in the ordinary manner and are 90 provided at their lower ends with the usual outwardly-disposed heel projections 9, which travel on the track formed by the upper edge 10 of the revolute cam ring or head 11.

The revolute cam ring or head 11 loosely 95 encircles the needle-cylinder 6 at the lower end thereof and is provided at its lower edge with an outturned bearing-flange 12, which loosely registers in the annular guide rabbet or groove 4, formed in the upper side of the base-ring 1, and said bearing-flange 12 of the cam ring or head is detachably retained within the said rabbet or groove 4 by means of a plurality of retaining-plates 13, detachably

secured on the upper side of the base-ring 1 by means of the screws or similar fasteners 14 and having their inner edges overlapping the peripheral edge of the flange 12, as plainly illustrated in Figs. 1 and 2 of the drawings. The mounting of the cam ring or head 11 in the manner described permits this ring or head to freely revolve or rotate around the stationary needle-cylinder, while at the same time permitting the ready removal and replacing thereof whenever necessary.

The upper track edge 10 of the revoluble cam ring or head 11 lies for its greater portion in a horizontal plane, but at one side of the ring or head is downwardly curved on the arc of a circle, as at 15, at which point the ring or head 11 has rigidly fastened to the outer face thereof a segmental cam-supporting plate 16, to the inner concaved side of which cam-supporting plate are fitted the needle actuating or controlling cams 18, 19, and 20. The main cam 18 is of an approximately triangular shape, with its apex disposed downwardly and having its inclined edges preferably compoundly curved, as at 19^a, to insure a proper reciprocation or movement of the knitting-needles, and said cam is supported in place by an adjusting-screw 20^a, projecting through a vertically-disposed slot 21 in the cam-supporting plate 16 and working in a short longitudinally-disposed slot 22, formed in the adjusting-lever 23, arranged in the outer face of the cam-supporting plate 16 and pivoted at one end thereto. The adjusting-lever 23 and its supporting screw connection with the main cam 18 provides for the vertical adjustment of said cam to enable the tension of the stitch to be varied within certain limits, and these parts of the machine are the same in construction and operation as the corresponding parts disclosed in my former patent No. 560,712. The cams 19 and 20 are respectively the right and left switch cams or dogs and are pivoted at their inner ends, as at 21^a, to the inner side of the cam-supporting plate 16, respectively, at opposite sides of the downwardly-pointing rounded apex or nose of the main cam 18, and all of said cams 18, 19, and 20 are arranged above and in the vertical plane of the downwardly curved portion of the track to form sinuous passages for the travel of the heel projections 9 of the reciprocating needles, it being understood that as the cam-ring is rotated in one direction the heel projections or ends of the needles will enter between one of the switch cams or dogs and the adjacent edge of the main cam 18 and pass out of the cam-space between the opposite switch cam or dog 6c and the adjacent curved track edge 15, as plainly illustrated in Fig. 4 of the drawings, and when the rotation is reversed the position of these dogs must also be reversed, which can be accomplished by the proper manipulation of the needles in the usual way, as fully explained in my former patent herein referred to. At this point it may be observed

that the construction and operation of the cams 18, 19, and 20 are in all respects similar to the construction and operation of the corresponding cams in my former patent, the only material difference residing in the manner of mounting the cams on the cam-ring and the shape of the inclined edges of the main cam 18.

To provide for a rotation of the cam ring or head 11 on the base-ring and around the needle-cylinder, the said ring or head has projected upwardly from the cam-supporting plate 16 thereof an upright crank-supporting bracket 22^a. This crank-supporting bracket 22^a is provided at the top thereof with a V-shaped support 23^a, having the horizontal divergent stop-arms 24, formed in their inner edges, near their outer ends, with the notches 25 or recesses 25, and having their outer ends joined with the upper ends of a pair of upright legs or standards 26, arising from the top edge of the cam-supporting plate 16. The V-shaped support 23^a at the top of the bracket 22^a is provided at its apex with a central bearing-plate 27, arranged above the vertical center of the needle-cylinder and having pivoted thereto by means of the pivot-bolt 28 the inner end of the pivotal or swinging crank arm or lever 29, having at its outer end a hand-grasp 30.

At a point intermediate its ends the pivotal crank arm or lever 29 is provided with a longitudinally-disposed slot 31 and a pair of pendent retaining-flanges 32, between which is arranged the heel-block 33 at the upper end of a vertically-disposed yarn-guide 34, and an adjusting-screw 35 is arranged in the slot 31 and engages with said heel-block 33 to provide for adjusting the yarn-guide 34 toward and from the needles, as may be required by the particular kind of knitting to be done. At its lower end the adjustable yarn-guide 34 is provided with a plate portion 36, having formed therein a guide-eye 37, through which the yarn 38 passes to the hooks of the needles, and said yarn is carried to the eye 37 through the guide eye or opening 39, formed in the crank arm or lever 29 at an intermediate point. In operating the machine the crank arm or lever 29 is grasped and thrown against one of the stop-arms 24 of the crank-supporting bracket, and since this bracket is rigidly connected with the cam-ring a continued pressure on the crank arm or lever will provide for the rotation of the cam ring or head and a consequent operation of the needles to provide for knitting the fabric. To reverse the machine, the cams are first properly adjusted and the crank arm or lever 29 moved in an opposite direction against the other stop-arm 24, and at this point it will be noted that the notches or recesses 25 of said stop-arms receive therein the retaining-flanges 32 when the crank arm or lever is pressed thereagainst.

The yarn for the machine is carried by a yarn-carrier 40, which yarn-carrier is rigidly connected with the ring 11, so as to rotate

therewith, and this connection with the cam ring or head is effected through the medium of a supporting-leg 41, rigidly fastened at one end, preferably by a slot-and-screw connection 42, to the ring 11 at the side diametrically opposite the cam-supporting plate 16. The supporting-leg 41 of the yarn-carrier has projected laterally therefrom a horizontal spindle 43, adapted to have detachably and loosely fitted thereon the spool or bobbin 44, which carries the yarn 38, and said leg 41 is further provided with an upper horizontal arm portion 45, on which is supported the upright standard 46. The upright standard 46 is provided at its lower end with an attaching-foot 47, pivotally fastened to the horizontal arm portion 45 of the leg 41 by means of a vertical pivot-pin 48, which permits the standard to turn axially, and thereby be swung in a lateral direction away from the needle-cylinder, so as to be entirely out of the way of the hands when threading or adjusting the parts of the machine in and around the needle-cylinder. The said laterally-swinging upright standard 46 is provided at its upper end with a horizontal cross-arm 49, which cross-arm is provided near one end with a guide-opening 50 and adjacent to such guide-opening with a locking-notch 51 for the take-up spring or wire 52. The take-up spring or wire 52 arches over the cross-arm 49, above the same, and is coiled at its upper end to form a terminal guide-eye 53 for the yarn, and the lower end of said spring or wire 52, which is bent into an approximate L shape, is connected to a pivot-plate 54, pivotally mounted intermediate its ends, as at 55, on the standard 46 at a point between the upper and lower ends of said standard, and below the pivot 55 the plate 54 has connected thereto one end of a retractile tension-spring 56, the other end of which spring detachably engages with the hook 57, projected laterally from a channeled adjusting-plate 58, slidably embracing the standard 46 near its upper end and having a slot-and-screw connection 59 therewith to provide for regulating the tension of the spring 56, and consequently the tension of the take-up wire 52. This take-up wire under ordinary conditions of knitting is engaged at its intermediate portion within the locking-notch 51 at one end of the cross-arm 49.

In conjunction with the take-up wire 52 there is employed a yarn-lock 60, having a guide-eye 61 at one terminal and bent at its opposite end into a lock-loop 62, extending over the cross-arm 49. At the looped end 62 thereof the yarn-lock 60 is pivoted to the said cross-arm 49, so that it can readily swing up and down to bind the yarn on top of said cross-arm or to allow the yarn to pass through the guides 50, 61, 53, 39, and 37 freely to the needles. When the take-up wire 52 is engaged in the locking-notch 51, its upper end is depressed toward the guide-eye 61 at one end of the pivotal yarn-lock 60, so that the lock or clamping-loop 62 will not bind on the

yarn, but will permit the free feed thereof to the needles, and this is the position of the parts on the yarn-carrier when all of the needles of the machine are in operation and the cam ring or head is being rotated continuously in either direction. However, when only a portion of the needles are in operation, as when knitting the heel in a stocking, and the cam ring or head is moved back and forth the take-up wire 52 is released from the notch 51, thereby elevating the yarn-lock 60 and causing the loop 62 thereof to pinch the yarn on top of the cross-arm 49, and the said take-up wire will then serve to take up the slack in the yarn without drawing the latter from the bobbin. Substantially the same operation is carried out by the take-up wire and yarn-lock disclosed in my former patent herein referred to; but in the present invention the take-up wire is arranged and mounted differently from the corresponding part shown in the patent and is more effective in its operation to provide for properly taking up the slack of the yarn and placing any tension desired thereon.

In the operation of the machine it is necessary to keep the fabric properly stretched, and to provide for this I employ a work-holding spider 63, essentially comprising a plurality of radially-disposed curved hook-arms 64, radiating from a common center and provided at their outer terminals with hooks 65, engaging with the fabric, and in Figs. 1 and 2 of the drawings these hooks are shown to engage the yarn to provide for holding the same when the needles are making the initial stitches. The said spider 63 has projected from its under side a pendent hook-rod 66, carrying a plurality of detachable weights 67, which provide for placing a proper tension or stretch on the knitted fabric, and it will of course be understood that any number of these weights may be employed according to the kind of work or fabric being knitted.

Having described the essential features of the machine it is to be noted that the needle-cylinder and the cam ring or head are designed to be constructed in various sizes, so as to make various sizes of fabric, and it will also be understood that various changes in the form, proportion, and the minor details of construction may be resorted to without departing from the principle or sacrificing any of the advantages of this invention.

Having thus described the invention, what is claimed, and desired to be secured by Letters Patent, is—

1. In a circular-knitting machine, the stationary needle-cylinder, a revoluble cam ring or head carrying the needle-controlling cams and having projected outwardly from one side thereof an upright crank-supporting bracket overhanging the cylinder, and a crank arm or lever connected with the bracket at a point above the vertical center of the needle-cylinder and having a pendent yarn-guide, substantially as set forth.

2. In a circular-knitting machine, the sta-

- tionary needle-cylinder, a revolute cam ring or head carrying the needle-controlling cams, a crank arm or lever connected with the cam ring or head, and a pendent vertically-disposed yarn-guide having at its upper end a heel-block adjustably interlocked with the crank arm or lever and provided at its lower end with a guide-eye for the yarn, substantially as set forth.
3. In a circular-knitting machine, a stationary base-ring supporting the needle-cylinder, a revolute cam ring or head loosely mounted on the base-ring, a separate cam-supporting plate fitted to the ring or head and having an upstanding crank-supporting bracket, needle-controlling cams arranged at and fitted to the inner side of said cam-supporting plate, and a crank arm or lever connected with said supporting-bracket above the plane of the needle-cylinder, substantially as set forth.
4. In a circular-knitting machine, the stationary needle-cylinder, a revolute cam ring or head carrying the needle-controlling cams and having a rigid crank-supporting bracket overhanging the cylinder and provided with a bearing-plate arranged above the vertical center of said cylinder, said bracket being also provided with stops and a crank arm or lever having a pivotal connection with said bearing-plate and adapted to move independently between said stops, said crank arm or lever also having a yarn-guide, substantially as set forth.
5. In a circular-knitting machine, the stationary needle-cylinder, a revolute cam ring or head carrying the needle-controlling cams, and a crank arm or lever connected with the cam ring or head and having a limited movement in opposite directions independent of the latter, said arm or lever having a yarn-guide, substantially as set forth.
6. In a circular-knitting machine, the stationary needle-cylinder, a revolute cam ring or head carrying the needle-controlling cams and having a crank-supporting bracket provided with spaced stops, and a crank arm or lever pivotally connected with the bracket at a point above the vertical center of the needle-cylinder and adapted to be moved against either of said stops, said arm or lever having a pendent yarn-guide, substantially as set forth.
7. In a circular-knitting machine, the needle-cylinder a revolute cam ring or head carrying the needle-controlling cams and having a crank-supporting bracket provided with spaced stops, and a crank arm or lever pivotally connected with the bracket and adapted to be moved against either of the stops thereof, said crank arm or lever having a yarn-guide substantially as set forth.
8. In a circular-knitting machine, the needle-cylinder, a revolute cam ring or head carrying the needle-controlling cams and having projecting upwardly from one side thereof an upright crank-supporting bracket com-

prising a pair of spaced upright legs or standards and a horizontal V-shaped support connected with the upper ends of said legs or standards, said V-shaped support having a pair of divergent stop-arms, and a crank arm or lever pivotally connected at one end to the V-shaped support at the apex thereof and adapted to be moved against either of said stop-arms, substantially as set forth.

9. In a circular-knitting machine, the needle-cylinder, a revolute cam ring or head carrying the needle-controlling cams and having at one side an upright crank-supporting bracket provided with horizontal spaced stop-arms, a crank arm or lever pivotally connected with the bracket and having a play between the arms thereof, and a vertically-disposed yarn-guide supported by said crank arm or lever, substantially as set forth.

10. In a circular-knitting machine, the needle-cylinder, a revolute cam ring or head carrying the needle-controlling cams and having at one side an upright crank-supporting bracket provided with horizontal spaced stop-arms overhanging the needle cylinder, a crank arm or lever pivotally connected with the bracket and having a play between the stop-arms thereof, and a pendent vertically-disposed yarn-guide having at its upper end a heel-block adjustably connected with the crank arm or lever and at its lower end a guide-eye through which the yarn passes to the needles, substantially as set forth.

11. In a circular-knitting machine, the needle-cylinder, a revolute cam ring or head carrying the needle-controlling cams and having a crank-supporting bracket, a crank arm or lever connected with the bracket and having a limited movement in opposite directions independently thereof, said crank arm or lever being provided intermediate its ends with a guide eye or opening for the yarn, and a pendent yarn-guide provided at or near its lower end with a guide-eye and having its other end adjustably connected with the crank arm or lever contiguous to the guide eye or opening, substantially as set forth.

12. In a circular-knitting machine, a stationary base-ring supporting the needle-cylinder, a revolute cam ring or head loosely mounted on the base-ring and having a downwardly-curved track portion at one side, a segmental cam-supporting plate fitted to the ring or head at the downwardly-curved portion thereof, and having an upstanding crank-supporting bracket, the needle-controlling cams arranged at the inner side of said cam-supporting plate and lying above and in the vertical plane of said downwardly-curved track portion, and a crank arm or lever connected with said supporting-bracket, substantially as set forth.

13. In a circular-knitting machine, the needle-cylinder, the cam ring or head, means for causing a relative movement between the needle-cylinder and the cam ring or head, and a yarn-carrier arranged at one side of the nee-

dle-cylinder and having a pivotal standard carrying guide-eyes for the yarn, substantially as set forth.

14. In a circular-knitting machine, the needle-cylinder, a revolute cam ring or head carrying the needle-controlling cams, means for rotating said ring or head, and a yarn-carrier rigidly connected with the ring or head and having a laterally-swinging standard carrying 10 guide-eyes for the yarn, substantially as set forth.

15. In a circular-knitting machine, the needle-cylinder, a revolute cam ring or head, means for rotating said ring or head, a yarn-carrier rigidly connected with the ring or head and having a laterally-swinging standard, and a bobbin-support and guide-eyes for the yarn fitted to said carrier, substantially as set forth.

16. In a circular-knitting machine, the needle-cylinder, a cam ring or head, means for causing a relative movement between the cylinder and the cam ring or head, a yarn-carrier arranged at one side of the cylinder and having an upright standard provided at its upper end with the cross-arm having a locking-notch at one end, and a guide-opening for the yarn contiguous to the notch, a pivotal yarn-lock mounted on the cross-arm, a take-up wire having a pivotal support at one end on the standard and at its other end a guide-eye to receive the yarn from said lock, the intermediate portion of the take-up wire being adapted to engage in said locking-notch, and a tension device connected with the take-up wire at or contiguous to the pivoted end thereof, substantially as set forth.

17. In a circular-knitting machine, the needle-cylinder, a revolute cam ring or head,

means for rotating said ring or head, a yarn-carrier having a bobbin-spindle, and an upright standard supported by and carried with the ring or head, said standard being provided at its upper end with a cross-arm having a locking-notch at one end, a pivotal yarn-lock mounted on the cross-arm, a take-up wire having a pivotal support at one end on the standard, and at its other end a guide-eye to receive the yarn from said lock, the intermediate portion of the take-up wire being adapted to engage in said locking-notch, 40 a vertically-movable plate adjustably fitted to said standard, and a tension-spring having its opposite ends respectively connected with said plate and the pivotal support or end of the 45 take-up wire, substantially as set forth.

18. In a circular-knitting machine, the needle-cylinder, a cam ring or head, means for causing a relative movement between said cylinder and the cam ring or head, a yarn-carrier arranged at one side of the cylinder and having an upright standard, a bobbin-support fitted to the yarn-carrier, a yarn-lock mounted on the standard, a pivotally-supported spring take-up wire coöperating with 60 the yarn-lock and having an interlocking engagement with the standard, and a variable tension device having connection with the take-up wire at or contiguous to the pivoted portion thereof, substantially as set forth. 70

In testimony that I claim the foregoing as my own I have hereto affixed my signature in the presence of two witnesses.

ASHLEY J. GULICH.
